UNITED STATES PATENT OFFICE.

JOHN W. LINZEE, JR., OF BOSTON, MASSACHUSETTS.

REINFORCED CONCRETE CONSTRUCTION.

No. 890,428.

Specification of Letters Patent.

Patented June 9, 1908.

Application filed March 29, 1907. Serial No. 365,347.

To all whom it may concern:

Be it known that I, JOHN W. LINZEE, Jr., of Boston, in the county of Suffolk and State of Massachusetts, have invented certain new and useful Improvements in Reinforced Concrete Constructions, of which the following is a specification.

This invention relates to concrete and steel constructions, being particularly applicable for floor beams, arches and trusses, and also capable of employment in walls, columns, etc.

The object is to reinforce concrete beams by means of longitudinal tension bars and transverse shear bars so as to provide for the proper transference of stress from the shear bars into the concrete and into the horizontal bar more directly than hitherto, and as an aid to skin friction.

Another object is to bend the shear bars intermediate their ends so as to form from them elements which are respectively inclined and perpendicular to the longitudinal bars, thereby combining in a single structure the principle of inclined tension bars with vertical concrete compression members, together with the principle of the vertical tension bars with inclined concrete compression members, the constructions embodying these principles being in different planes and connected together so that the concrete in all parts of the structure may be subjected only to compression, while all the tensile stresses are taken by the metal, so as to obtain the maximum strength with the minimum expenditure of material, and to avoid useless weight.

A further object is to arrange the inclined member of each shear bar so as to overlap the vertical member or members of adjacent bars so as to form a net-work whereby it will be impossible to pass a section through the structure transverse to the longitudinal bar without cutting a shear bar before or simultaneously with the cutting of the longitudinal bar, for the purpose of resisting the shearing stresses by members arranged so as to oppose their tensile strength to such stresses.

The accompanying drawings show a number of ways in which the objects and principles of my invention may be carried out.

Figures 1 and 2 represent sectional views of concrete beams with longitudinal tension rods and a variety of arrangements of shear bars engaged therewith for carrying stresses

transversely of the beam. Fig. 3 represents a longitudinal sectional elevation showing the manner in which certain of the shear bars in Figs. 1 and 2 are arranged. Fig. 4 represents a sectional plan view of the structure shown in Fig. 1. Figs. 4^a and 4^b represent vertical sections taken on planes A—B and C—D, respectively of Fig. 4. Fig. 5 represents a cross section illustrating the manner in which one of the connections between the tension and shear bars may be used as a spacing means. Figs. 6 and 7 represent in detail a fragmentary section and elevation of one form of connection between the tension and shear bars. Figs. 8 and 9 represent similar views of a modification of this connection. Fig. 10 represents in elevation a further modification. Fig. 11 represents a sectional view of another modification. Fig. 12 represents a sectional elevation of a further modification of the same principle. Figs. 13, 14 and 15 represent two elevations and a cross section of a construction embodying similar principles in which a separate tie member is employed.

The same reference characters indicate the same parts in all the figures.

Referring first to Figs. 1, 2, 3, 4, 4^a, 4^b and 5, *a* represents a concrete beam which is to be understood as being typical of any concrete structure in which are embedded longitudinal tension bars *b*, *c* and *d*, and transverse shear bars *e* and *f*. Each of the shear bars is bent intermediate its ends and passes partially around one or more of the longitudinal bars, being embedded at its ends in the concrete adjacent the opposite side of the structure from the longitudinal bars. As indicated above, the longitudinal bars lie in the angles formed by the bends in the shear bars. The latter are further twisted or bent in longitudinal planes so as to form elements which are respectively inclined and perpendicular to the longitudinal bars. All the figures show the structure as a horizontal beam with the longitudinal bars *b*, *c* and *d* horizontal, and portions of the shear bars as vertical, and therefore for convenience, the terms "horizontal" and "vertical" will be used hereinafter in the specification to avoid circumlocution, it being understood, however, that the longitudinal bars may be either horizontal as when in a beam, or vertical as in a wall or column, and that the term "vertical" when applied to a shear bar means perpendicular to the longitudinal bar.

In every construction, whether two or more longitudinal bars are used, the shear bars are so located as to form respectively inclined and vertical members. Two elements of the same shear bar may be respectively inclined and vertical, as illustrated in Figs. 3, 4, 4^a, and 4^b, or both the elements of the same bar may be inclined, while the two end portions of the adjacent shear bar may be vertical. In any event, the inclined element crosses or overlaps the vertical element of the adjacent bar. This forms a net-work, as illustrated in Fig. 3, so that it is impossible to pass a transverse plane through the structure without cutting both a shear bar and the longitudinal bar. In constructions which have only inclined shear bars, a plane such as A—B (Fig. 3) could be passed without cutting any metal except the longitudinal bars, while when only vertical shear bars are employed, a vertical plane like C—D can be passed without intersecting the shear bar. Stresses tending to shear the structure may occur on either of these planes, which with the older constructions would be resisted mainly by the concrete. This resistance would be very slight in the case of the vertical shear plane, since the resistance to shearing of concrete is slight. With the net-work construction herein illustrated, a truss is formed of steel bars in which any transverse stress is opposed by a component of the tensile strength in at least one of the shear bars. This is due to the fact that no transverse section of the structure is without a shear bar.

Another result which is derived from having the inclined and vertical elements respectively, is that of combining in a single structure two standard truss systems. Referring to Fig. 4^a, which illustrates a section taken on line A—B of Fig. 4 as viewed in the direction of the arrow, the inclined elements of the shear bars *e* are shown between which the concrete forms vertical struts to support the loading on the upper side of the structure, as in the Pratt truss system. Fig. 4^b illustrates the central section of the beam looking in the direction of the arrow from the line C—D. In this figure the vertical elements of the shear bars are shown which are in tension, while the concrete between the metal elements is in compression on diagonal lines (illustrated by the arrows), forming inclined struts of concrete as in the Howe truss system. The outer section of the beam in which the inclined members of shear bars *f* lie, is the same as shown in Fig. 4^a. Thus the structure is formed of a series of trusses in which the several systems alternate, which are tied together by the transverse portions of the shear rods uniting the vertical and inclined elements respectively. The stresses of the metal bars are thereby transferred to the concrete, and vice versa, in the most effective possible manner so as to utilize practi-

cally all the concrete in compression, and to carry all tensile stresses in the metal. In this way beams and other structures may be made lighter and with greater economy of material.

It is to be understood that the reverse of the construction shown in Figs. 4, 4^a and 4^b may be employed, that is, that the outer members may be vertical and the inner ones inclined. It is to be borne in mind also that the inclined members extend upwardly toward the nearest end of the beam, so that on opposite sides of the center their inclinations are opposite, thus following out the usual principles of truss construction.

Fig. 2 shows a construction in which the truss principle is extended so as to form a truss in cross-section. Here the shear bars are not only provided with vertical and inclined elements, but certain elements such as those designated *e*³ and *f*³ are inclined transversely also so that they overlap in cross-section and transfer stresses from one side of the truss to the other. The members *e*³ and *f*³ may be either perpendicular to the longitudinal or inclined with respect thereto toward the adjacent end of the beam.

In Fig. 5, the shear bar *e* passes under the three longitudinal bars *b*, *c* and *d*, and is provided with wedges *i* which enter slots in the longitudinals and keep them at the proper distance apart. As this shear bar affords no connection for the central longitudinal, a shear bar *f* is provided in the center of the beam which is bent about the central bar *c*. Certain of the members of these shear bars are inclined, while others are vertical. Thus, the members of the bar *e* may both be inclined, while both ends of *f* are vertical, or the reverse may be the case.

I will now proceed to describe the connections for securing the shear bars and tension bars together.

In each of the figures numbered 6 to 15 inclusive, the tension bar is represented by *b* and the shear bar by *e*. In Figs. 6 and 7, the shear bars are formed with integral wedge tongues *i* on the inner surface of the central part of the bend in the shear bar. These tongues enter slots, indentations, or recesses *j* in the under side of the tension bar, and when driven in by the blow of a hammer, are held frictionally and prevent slipping of one bar relatively to the other. There must be enough metal in the wedge tongue to take the horizontal component of the stress in the shear bar and transfer it to the tension bar without danger of stripping off the tongue. At the points *k* where the recesses or slots *j* in the tension bar are formed, the bar is enlarged, having enough metal in the protuberances *k* to compensate for the amount removed in making the recesses *j*. Such enlargements also serve as anchors for the longitudinal bars, preventing endwise movement thereof.

in the concrete. The shear bars may also be so shaped at the portions which come in contact with the tension bars as to give as great a bearing area as possible. These bars 5 may be of any desired shape at all other points, but are preferably flattened at the contacting points, or they may be still further flattened and widened, as shown in Fig. 10.

10 Figs. 8 and 9 show the shear bars carried around so as to entirely surround the tension bar and are crowded together above the latter by a wedge collar *l*.

15 In Fig. 11, the wedge *i'* is separate and is driven through the shear bar before entering the socket *j* in the tension bar. The shear bars shown in these figures are preferably bent on a radius of curvature less than that of the tension bar at the zone of engagement.

20 Thus when they are forced together, the tension bar spreads apart the members of the shear bar, putting the outer elements of these members under a compressive strain whereby they are held tightly against the 25 tension bar and grip it frictionally, which assists the wedges in tightly securing the bars together.

Fig. 12 shows a reversal of the construction above illustrated, in which the wedge is 30 formed on the tension bar and is forced into a socket in the shear bar.

In Figs. 13, 14 and 15 the shear bar does not embrace the tension bar, but is held against the top of the latter by a binding 35 ring or collar *n*. The top of the tension bar is preferably flattened, and the side of the shear bar which comes next it is also flattened to provide an extended bearing and prevent twisting. Either the lugs or wedge- 40 tongue may be provided to secure the ring to the tension bar, while the shear bar is frictionally wedged between the ring and tension bar, having an enlargement *o* at the point where it is bent for this purpose. An 45 integral wedge protuberance *p* may also be formed upon the tension bar to increase the wedging action between the latter and the shear bar, and if desired, the wedge tongue *i* may be omitted altogether. If this is done, 50 the shear bar and ring are forced horizontally over the enlargement *p* so as to secure a tight engagement of the wedging action of the latter.

It will be noted that in Figs. 6 to 12 inclusive, the sides of the socket *j* embrace the wedge-tongue *i* and act as shoulders or abutments which restrain the tongue against movement in any direction, while the enlargement *o* on the shear bar, and *p* on the 60 tension bar, constitute integral wedges or abutments which by means of the ring *n* bind the bars together.

In Fig. 5, the principle of the tongue and slot connection is illustrated as applied to a 65 beam in which there are three longitudinal

tension bars, and a single shear bar passing under all three of them. It may also be applied where there are more than three or where there are only two longitudinals. In any case, the wedges serve as spacers to keep 73 the longitudinal bars at the proper distance apart, and as securing means to prevent slipping of the shear bars along the longitudinals. It is to be understood that one or another of these securing connections is intended to be used with each of the shear bars 75 in the arrangements shown in Figs. 1, 2 and 3.

I claim:

1. In a reinforced concrete structure, the 80 combination of a plurality of longitudinal tension bars in the same horizontal plane, and shear bar elements in different vertical longitudinal planes, the elements in one of the vertical planes being vertical and those 85 in another plane being inclined, and the adjacent vertical and inclined elements in the different planes being connected by integral horizontal transverse connecting members beneath the longitudinal bars; the said construction forming parallel truss systems bonded together by the connecting members.

2. In a reinforced concrete structure, the 90 combination of a plurality of longitudinal tension bars in one plane, shear bar elements 95 respectively perpendicular and inclined with respect to said longitudinal bars arranged in separated longitudinal parallel planes perpendicular to the first-named plane, the perpendicular shear bar elements being in one of 100 the parallel planes and the inclined members in another, whereby parallel truss systems are provided, and direct transverse connecting members integrally uniting the perpendicular and inclined elements of each couple 105 together, said elements and members embracing a plurality of longitudinal bars and resisting separation thereof with the entire tensile strength of the transverse members.

3. In a reinforced concrete structure, the 110 combination of a plurality of longitudinal tension bars spaced apart from each other, and shear bars bent to form three sides of an embracing structure within which at least 115 two of the longitudinal members are included; the outer elements at one end of said shear bars being inclined to the longitudinal bars and lying in one plane which includes one of the longitudinal bars, forming therewith a truss having intermediate vertical 120 concrete struts; the elements at the opposite ends of the shear bars being in a different plane, parallel to the first-named plane, with another longitudinal bar and perpendicular thereto, forming therewith a truss having intermediate inclined concrete struts; and the intermediate members of the shear bars extending straight from one plane to the other and bonding the truss structures together.

4. In a reinforced concrete structure, a lon- 130

5 longitudinal tension bar, a shear bar bent at an angle so as to form a vertical and an inclined tension element, engaging the longitudinal bar at the bend, and an integral wedge formed on one of the bars coating with the other bar at the point of engagement, to prevent relative motion.

5. In a reinforced concrete structure, the combination of longitudinal tension bars and 10 transverse shear bars bent to inclose a bar and to form members extending throughout nearly the entire thickness of the concrete, certain of said members being inclined and the others being perpendicular with respect 15 to the longitudinal bars and the inclined members longitudinally overlapping the adjacent perpendicular members, said shear bars having protuberances at the bends and the longitudinal bars having slots to receive 20 said protuberances, the longitudinal bars being enlarged at the points where the slots are formed, whereby the tensile strength of these bars is preserved and anchoring enlargements are provided.

25. 6. In a reinforced concrete structure, the combination of longitudinal and transverse members, certain of said members having indentations extending partially therethrough, and having an enlargement adjacent each indentation and on the side opposite thereto, and other of the members having wedging projections adapted to be readily inserted in the indentations, whereby the members may be readily assembled during the construction 35 of the work.

7. A reinforcing structure for concrete consisting of longitudinal and transverse members, certain of said members having slots at intervals throughout their length and the 40 other of said members having protuberances extending into, and gripped by the walls of, said slots, and the members in which the

slots are formed having compensating enlargements adjacent the slots.

8. A reinforcing structure for concrete consisting of separate reinforcing members, certain of said members having integral wedges and the other members having correspondingly shaped slots into which said members are driven, and by which they are gripped thereby preventing motion at their point of contact.

9. In a reinforced concrete structure, a longitudinal tension bar, a shear bar having a bend and being engaged with the longitudinal bar at the bend, a wedge member on said shear bar adjacent to the bend, and a co-operating abutment on the longitudinal bar with which said wedge member is engaged.

10. In a reinforced concrete structure, a longitudinal tension bar, a shear bar having a bend and being engaged with the longitudinal bar at the bend, a wedge member on said shear bar adjacent to the bend, a coöperating abutment on the longitudinal bar 60 with which said wedge member is engaged, and a collar surrounding said shear bar to retain the wedge member and abutment in contact.

11. In a reinforced concrete structure, a longitudinal tension bar, a shear bar bent about said longitudinal bar and provided with a wedge entering a slot in the longitudinal bar, and a collar surrounding the members of the shear bar adjacent to the longitudinal bar for causing the shear bar to grip the longitudinal bar.

In testimony whereof I have affixed my signature, in presence of two witnesses.

JOHN W. LINZEE, JR.
